US0D1114235S

(12) **United States Design Patent** (10) Patent No.: **US D1,114,235 S**
(45) Date of Patent: ** Feb. 17, 2026

(54) **FAN**

(71) Applicant: **Haibo Wang**, Ninghai (CN)

(72) Inventor: **Haibo Wang**, Ninghai (CN)

(**) Term: **15 Years**

(21) Appl. No.: **29/950,933**

(22) Filed: **Jul. 5, 2024**

(51) LOC (15) Cl. **23-04**

(52) U.S. Cl.

USPC **D23/383; D23/370**

(58) **Field of Classification Search**

USPC D23/370, 379, 380, 382, 332

CPC ... F04D 25/0606; F04D 29/329; F04D 29/703

(57) **CLAIM**

The ornamental design for a fan, as shown and described.

DESCRIPTION

FIG. 1 is a first perspective view of a fan showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the fan that form no part of the claimed design.
